UNITED STATES PATENT OFFICE.

BERT G. DUNHAM, OF HAWTHORNE, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed August 7, 1919. Serial No. 315,817.

To all whom it may concern:

Be it known that I, BERT G. DUNHAM, a citizen of the United States, residing at Hawthorne, in the county of Passaic, State 5 of New Jersey, have invented certain new and useful Improvements in Telephone-Exchange Systems, of which the following is a full, clear, concise, and exact description.

This invention relates to improvements in 10 telephone exchange systems and has particular reference to line switch circuits therefor.

Heretofore it has been customary to provide a line switch with a cutoff relay which 15 operates, upon the seizure of a trunk, to extend a calling line to a selector switch, whereupon the seized line or trunk is held busy by relays at said selector switch. In 20 systems of this character there is a slight time interval between seizure of the switch and the operation of the relay at the seized switch which renders the line busy.

An object of the present invention is to 25 avoid the time interval which exists between the actual seizure of a trunk or line and the application of a busy condition thereto.

A feature is to provide means at the line 30 switch for holding a seized trunk busy until the calling subscriber transmits impulses to operate a succeeding switch.

The inventive idea involved is capable of 35 receiving a variety of expressions some of which, for the purpose of illustrating the invention, are shown in the accompanying drawings; but it is to be expressly understood that said drawings are employed merely for the purpose of facilitating the 40 description of the invention as a whole and not to define the limits thereof, reference being had to the appended claims for this purpose.

In the drawings, Fig. 1 illustrates diagrammatically a circuit for a line switch having no normal position. Fig. 2 is a similar view of a circuit in which the switch is 45 returned to normal at the termination of a call.

Referring to the drawings and more particularly to Fig. 1, when a subscriber at 50 substation 1 removes his receiver from its switchhook to initiate a call, a circuit is closed for line relay 2 extending from grounded battery, right winding of said relay, back contact and inner armature of 55 cutoff relay 3, apparatus at substation 1,

left winding of relay 2 and back contact and outer armature of relay 3 to ground. Relay 2 energizes and by attracting its left armature applies ground to conductor 4 leading to the test terminal 5 of a connector 60 multiple, thus preventing seizure of the line of substation 1. By attracting its right armature, relay 2 short-circuits cutoff relay 3 which remains in this condition until relay 2 deenergizes in response to the first impulse 65 transmitted from the substation 1.

If the brushes 6, 7, 8 and 9 of the switch are resting upon the terminals of an idle trunk, an energizing circuit for relay 10 will be established extending from grounded 70 battery, winding, armature and back contact of motor magnet 11, the contacts of the right armature of relay 2, winding of relay 10, conductor 4 and left armature and front contact of relay 2 to ground. Motor magnet 11 is adjusted so as not to operate when 75 in series with either or both relays 3 and 10. By attracting its upper armatures relay 10 connects the calling line to the brushes 6 and 7 but the line is not extended to the 80 next succeeding switch owing to the short-circuiting of cutoff relay 3 by the line relay. The ground at left armature of relay 2 is now extended through the front contact and inner lower armature of relay 10 and brush 85 8 to the test terminal of the seized trunk, thus holding this trunk busy until relay 2 is deenergized. Relay 10 is then locked up 90 through its front contact and inner lower armature. When the subscriber at substa- 95 tion 1 operates the impulse sending device 12, the circuit for line relay 2 is opened and this relay then deenergizes. Release of relay 2 opens the short circuit for relay 3 which then energizes over the circuit extend- 95

ing from grounded battery, winding, armature and back contact of motor magnet 11, winding of relay 3, winding, front contact and inner lower armature of relay 10 and brush 8 to ground upon the busy test terminal of the seized selector switch. Energization of relay 3 extends the calling line through the inner armature and front contact thereof, the upper armatures of relay 10 and brushes 6 and 7 to the trunk of the 100 105 succeeding switch.

Let it now be assumed that the brushes of the switch are in engagement with the terminals of a busy trunk. When relay 2 is 110 energized as before cutoff relay 3 is again

short-circuited and the ground at the left armature of relay 2 is extended to one end of the winding of relay 10. The other end of said winding is also grounded from the test terminal of the busy trunk through brush 8, inner lower armature and back contact of relay 10 and right armature and outer front contact of relay 2. Relay 10 is thereby shunted and prevented from operating until the brushes of the switch engage an idle trunk which has no ground upon its test terminal. Energization of relay 2 establishes a circuit for motor magnet 11 extending from grounded battery, winding, armature and back contact of said magnet, front contacts and right armature of relay 2, back contact and inner lower armature of relay 10 and brush 8 to ground upon the busy terminal. This circuit being independent of the windings of either of the relays 3 or 10 will cause the motor magnet to operate and step the brushes of the switch until the terminals of an idle trunk are engaged, whereupon the operation of the switch is the same as previously described.

If the service of substation 1 is restricted, the front contact of the outer lower armature of relay 10 is connected to brush 9, as shown, so that upon the release of relay 2 when the first impulse is transmitted, the ground upon the test terminal of the seized trunk is extended through brush 8, inner lower armature and front contact of relay 10, conductor 4, left armature and back contact of relay 2, outer lower armature and front contact of relay 10 and brush 9 to the succeeding switch. Means (not shown) well known in the art are provided at the latter switch for preventing the establishment of the call initiated at the substation. One method of attaining this result is shown in the patent to Williams, No. 1,355,635, issued October 12, 1920.

At the termination of a successful call, the release of the selector switch connected to the line switch removes ground from the terminal engaged by brush 8 and thus opens the locking circuit for relay 10 which then releases. Relay 3 which is also maintained in this circuit thereupon releases and the switch is then in condition to extend another call, the brushes thereof remaining in the position assumed when the idle trunk was found.

On incoming calls to substation 1, if the line is idle and the connection is automatic, a ground will be extended from a connector switch through test terminal 5, conductor 4, left armature and back contact of relay 2, outer lower armature and back contact of relay 10, winding of cutoff relay 3, back contact, armature and winding of motor magnet 11 to grounded battery. Cutoff relay 3 energizes in this circuit and prevents the establishment of the energizing circuit

for line relay 2. If the connection is manual, the cutoff relay 3 is operated in the same manner by ground extending from contact 13, over the previously described circuit when an operator inserts a plug into jack 14. This ground on contact 13 is extended to terminal 4 and thus provides a busy test for the called line.

Referring now to Fig. 2, when a call is initiated at substation 14, line relay 15 is energized by a circuit extending from grounded battery, right winding of said relay, inner upper alternate contact of cutoff relay 16, back contact and left armature of relay 15, substation apparatus and outer upper alternate contact of relay 16 to ground. Relay 15 energizes, whereupon the energizing circuit therefor will extend through its left winding. In attracting its right armatures, relay 15 establishes a self-interrupting circuit for motor magnet 17 extending from grounded battery, winding, armature and back contact of said magnet, middle lower armature and back contact of relay 16, front contact and inner right armature of relay 15, brush 18 and front contact and outer right armature of relay 15 to ground.

Magnet 17 operates to step the brushes from normal onto the set of terminals of the first trunk leading to a succeeding switch. If this trunk is busy, this condition is denoted by ground upon the terminal engaged by brush 18 and this ground will be extended through the inner right armature and front contact of relay 15, the back contact and middle lower armature of relay 16 to one end of the winding of said relay. The ground upon the outer right armature and front contact of relay 15 is extended to the other end of the winding of relay 16 and this relay is thereby shunted and prevented from operating. Motor magnet 17 will therefore continue to operate over the previously described circuit until the terminals of an idle trunk are reached.

At this time no ground being on the terminal engaged by brush 18 the shunt for relay 16 will be removed and this relay will energize over a circuit extended from grounded battery, winding, armature and back contact of magnet 17, winding of relay 16 and front contact and outer right armature of relay 15 to ground. Magnet 17 is adjusted so as not to operate in this circuit. The ground upon the outer right armature of relay 15 is now extended through the innermost lower armature and front contact of relay 16 and brush 18 to the test terminal of the seized trunk and this ground maintains the trunk in this condition until relay 15 is released. Relay 16 is also locked up to this ground through its winding, innermost lower armature and front contact. The energization of relay 16 opens the original energizing circuit for

line relay 15 but this relay does not, at this time, release due to the circuit extending from grounded battery at the seized selector switch, brush 19, inner upper armature and alternate contact of relay 16, left winding of relay 15, apparatus at substation 14, alternate contact and outer upper armature of relay 16 and brush 20 to ground at said selector switch. Due to the continued energization of relay 15 the calling line is not extended to the succeeding switch at this time. The switch is now in condition for transmission of impulses from the calling substation and upon the first opening of the circuit for line relay 15 this relay deenergizes, and in so doing, extends the calling line through the back contact and left armature thereof. The left winding of relay 15 is now short-circuited and this relay will not energize again. When relay 15 deenergizes, the ground is removed from the outer right armature and front contact thereof, whereupon the seized trunk will be held busy at the selector switches. It will thus be apparent that the seized trunk leading to the selector switch is maintained busy by the line switch until the first impulse is transmitted from substation 14.

Upon the first step of the switch from its normal position a ground is continuously applied to brush 21 of the switch until the same is restored to normal, which ground will be applied to the test terminal 22 of the connector multiple and thus prevent seizure of the line of substation 14 by an incoming call.

If the service of substation 14 is restricted, brush 23 of the switch is connected to front contact of the outermost lower armature of relay 16 so that the ground at said armature will be extended through brush 23 to means, not shown, at the succeeding switch which will be energized to prevent the establishment of a call.

At the termination of a call from substation 14, the release of the selector switch, to which the line switch is connected in a manner well known in the art, will remove ground from the test terminal engaged by brush 18 and thus open the locking circuit for cutoff relay 16 which then deenergizes. A circuit is then established for motor magnet 17 extending from grounded battery, winding, armature and back contact of said magnet, middle lower armature and back contact of relay 16, brush 24, and the terminal engaged thereby, and back contact and outer right armature of relay 15 to ground. The magnet 17 operates to step the brushes of the switch over the associated terminals until the switch is restored to normal.

Assuming that substation 14 is idle when an incoming call is established through the connector multiple, a ground from a connector switch upon the test terminal 22 is ex-

tended from brush 21, normal terminal thereof, winding of cutoff relay 16, back contact, armature and winding of motor magnet 17 to grounded battery. Relay 16 will energize and thus prevent energization of line relay 15 when the subscriber at substation 14 responds to the incoming call by removing his receiver from the switchhook. Should the incoming call be established manually by the insertion of a plug into jack 25, the ground applied to contact 26 will operate in the same manner as that applied to terminal 22.

What is claimed is:

1. In a telephone system a subscriber's substation including an impulse sending device thereat, a telephone line extending from said substation, a plurality of other lines, an automatic switch for seizing one of said other lines and interconnecting the same with said telephone line, means at said automatic switch for holding the seized line busy until said impulse sending device is operated, and means at a succeeding switch for thereafter holding said seized line busy. 90

2. In a telephone system, a subscriber's substation including an impulse sending device thereat, a telephone line extending from said substation, a plurality of other lines, an automatic switch for seizing one of said other lines and interconnecting the same with said telephone line, means at said automatic switch for holding the seized line busy until said impulse sending device is operated, and means at said automatic switch for removing the busy condition thereat when the first impulse is transmitted by said sending device. 95

3. In a telephone system, an incoming line, a plurality of outgoing lines, an automatic switch for seizing one of said outgoing lines and interconnecting the same with said incoming line, a relay at said automatic switch arranged when operated to hold the seized outgoing line busy subsequent to the seizure thereof and means responsive to the transmission of impulses over the incoming line for causing the release of said relay. 105

4. In a telephone system, a subscriber's substation including an impulse sending device thereat, a telephone line extending from said substation, a plurality of other lines, an automatic switch for seizing one of said other lines and interconnecting the same with said telephone line, a relay at said automatic switch for holding the seized line busy until said impulse sending device is operated, and means at a succeeding switch for thereafter holding said seized line busy. 115

5. In a telephone system, an incoming line, a plurality of outgoing lines, an automatic switch for seizing one of said outgoing lines and interconnecting the same with

4

said incoming line, a cutoff relay for said switch, means for preventing operation of said cutoff relay upon the seizure of said outgoing line and means responsive to impulses 5 subsequently sent over the incoming line for causing the operation of said relay.

6. In a telephone system, a subscriber's substation including an impulse sending device thereat, a telephone line extending 10 from said substation, a plurality of other lines, an automatic switch for seizing one of said other lines and interconnecting the same with said telephone line, a cutoff relay for said switch, and means for preventing 15 operation of said cutoff relay until said impulse sending device is operated.

7. In a telephone system, a subscriber's substation including an impulse sending device thereat, a telephone line extending from said substation, a plurality of other lines, 20 an automatic switch for seizing one of said other lines and interconnecting the same with said telephone line, a cutoff relay for said switch, a line relay for preventing operation of said cutoff relay subsequent to the 25 seizure of said line and for holding said line busy until said impulse sending device is operated, and means at a succeeding switch for thereafter holding said line busy.

In witness whereof, I hereunto subscribe 30 my name this 4th day of August A. D. 1919.

BERT G. DUNHAM.
